UNITED STATES PATENT OFFICE.

OLIVER P. SCHRIVER, OF NEWPORT, KENTUCKY.

DESIGN FOR A FENCE-WIRE RATCHET-FRAME.

SPECIFICATION forming part of Design No. 26,222, dated October 27, 1896.

Application filed April 30, 1896. Serial No. 589,783. Term of patent 7 years.

To all whom it may concern:

Be it known that I, OLIVER P. SCHRIVER, a citizen of the United States, residing at Newport, in the county of Campbell and State 5 of Kentucky, have invented and produced a new and original Design for a Fence-Wire Ratchet-Frame; and I do hereby declare the following to be a full, clear, and exact description of the same, reference being had to the accompanying drawing, which forms a part of this specification.

In the drawing, which is a perspective view of a fence-wire ratchet-frame embodying my design, A represents a back plate, and B C 15 are flat side plates projecting therefrom. Side plate B has a circular opening b and a

molding or bead b', which bead runs around the outer margin of said plate, a portion of said bead being concentric with said opening. The other side plate C has a circular opening 20 c and a molding or bead similar to the one seen at b'.

I claim as new and of my invention—

The design for a fence-wire ratchet-frame, as herein shown and described. 25

In testimony whereof I affix my signature in presence of two witnesses.

OLIVER P. SCHRIVER.
